UNITED STATES PATENT OFFICE.

REES F. PARRY, OF DALLAS, TEXAS.

LOOSE-LEAF BINDER.

No. 847,364.

Specification of Letters Patent.

Patented March 19, 1907.

Application filed October 6, 1906. Serial No. 337,766.

To all whom it may concern:

Be it known that I, REES F. PARRY, a citizen of the United States, residing at Dallas, in the county of Dallas and State of Texas, have invented certain new and useful Improvements in Loose-Leaf Binders, of which the following is a specification.

This invention relates to loose-leaf binders such as are used for record, minute, journal, or sales books and various other records.

My invention is especially adapted for use in public offices in which records of deeds, wills, court-minutes, &c., are kept subject to public inspection, also by corporations and commercial and financial concerns.

The invention will be described in connection with the accompanying drawing, in which—

Figure 1 is an end view of a book embodying the invention opened at one side, so that the front leaf or leaves may be removed. Fig. 2 is a similar view of the book opened at the other side. Fig. 3 is a transverse section of a portion of the book, taken through one of the binding-posts. Fig. 4 is a longitudinal section on the line 4 of Fig. 3. Fig. 5 is a partial plan view illustrating the devices for locking the covers in place. Fig. 6 is a view similar to Fig. 4, but showing the opposite end of the book. Fig. 7 illustrates one means for locking and unlocking the book. Fig. 8 illustrates another means for locking and unlocking the book. Fig. 9 is a plan view of a portion of one of the fly-leaves of the book, and Fig. 10 is an end view of the leaf shown in Fig. 9.

Referring to the drawings, 11 12 indicate the two covers of the book, which may be of any desired material and construction, and 40 13 indicates the back. Adjacent to the hinge which connects each cover to the back is a locking-slide 14, preferably contained in a metal casing 15 of rectangular cross-section, which casing is suitably connected to the binding. Each slide 14 is provided with a plurality of perforations 16 and is normally pressed against a stop 17 by a spring 18, interposed between the shoulder or seat 19 of the slide 14 and an abutment 20 on the case 45 15. The spring is inclosed within the casing, and the slide 14 may be cut away, as shown, to make room for it.

The openings 16 in the locking-slides register with openings in the casings 15, and the 50 corresponding openings in the two casings are opposite to each other when the book is

closed. A plurality of independent or detachable posts or rods 21 extend from cover to cover adjacent to the back, each post being adapted to enter two opposite openings 60 in the casings 15 and to be automatically locked to the covers by the slides 14. For the purpose of connecting the posts to the slides the posts are provided with notches or recesses 22 and preferably with beveled ends 65 23, which cause them to pass more readily into the openings of the casings and the slides.

As shown, the covers are provided with flexible or hinge portions 24 just in front of 70 the casings 15, and the casings are hinged at their rear sides to the back of the book. The casings are preferably connected by hinge-joints 25 to the curved plates 26, which conform to the curvature of the back of the 75 book and are preferably incased in the back and form a part thereof. The casings may be connected by a series of these back-plates or by a single continuous back-plate extending throughout the entire length of the book 80 or the greater portion thereof. These back-plates serve to stiffen the back of the book and preserve its shape, and also to hold the casings 15 in proper relation to the back and to each other, and they are especially useful 85 in maintaining the openings in the casings directly opposite each other, so that the posts 21 will readily enter the casings and the openings in the locking-slides when the book is closed.

In the drawings, 27 indicates the leaves of the book, and 28 a tab or marker, which is connected to one of the leaves for a purpose to be hereinafter explained. Just within the cover, on each side of the book, I preferably 95 place a fly-leaf 29, which is hinged at 30 to a stiff strip 31. The strips 31 are preferably reinforced by flat thin metal plates 32. Thus, as shown, the strips 31 are each composed of a flat metal plate 32, surrounded by 100 a cover or case of leather or fabric, the edges of which are connected to the fly-leaf proper, 29. Each of the strips 31 is provided with a series of openings 33, which receive the posts 21 and cause them to register with the openings in the casings 15. The posts 21 are preferably round in section and of substantial diameter so as to be stiff and strong, and the perforations in the loose leaves 27 and the strips 31 are also preferably round and 105 slightly larger than the posts.

Referring to Fig. 7, 34 indicates a key

adapted to be inserted in one end of the casing 15 to push the locking-slide 14 back against the tension of the spring 18 and disengage it from the posts 21. In this manner 5 either cover may be unlocked from the posts and thrown back, as illustrated in Figs. 1 and 2, leaving the ends of the posts exposed and the leaves in condition to be removed from the book. In Fig. 8 I have shown a screw 10 35 threaded into a block 36, which is fixed in the end of the casing 15. The inner end of the screw is swiveled in a projection 37 of the slide 14, so that the slide must move in either direction with the screw. For operating 15 this slide a suitable screw-driver key 38 is provided. With this screw-driver key the slide may be engaged with or disengaged from the posts.

When the copying of records in the books 20 is completed, my binder is transformed into a permanent binding by securing the slides 14, so that they cannot be released from the posts 21. This may be accomplished in various ways; but I preferably use the means 25 illustrated in Fig. 6, in which 39 indicates a screw which is inserted in a suitably-threaded opening in the end of the casing 15, one end of the screw being against the slide 14 and holding said slide in engagement with 30 the posts 21, while the other end of the screw is flush with the end of the casing or within the end of the casing, so that it cannot be readily tampered with. For convenience I provide screws 39, having handles 40 and 35 partially cut away at 41, so that the handles may be readily broken off. If additional security is required, the screws 39 may be soldered or otherwise rigidly connected with the casings. It will be evident that other 40 means may be employed for locking the slides to permanently connect the covers with the posts 21 and the leaves upon said posts.

Assuming that the front page of the book 45 is on top, as shown in Fig. 1, and the rear page on top, as shown in Fig. 2, the preferred manner of using the book is as follows: When the first record is to be placed in the book, the book is opened, as shown in Fig. 1, the 50 fly-leaf removed, and the first page then removed and the record made upon it by means of a type-writer or otherwise. The fly-leaf is then replaced, the book closed and locked and turned over and the opposite side 55 unlocked, as in Fig. 2. At starting the leaf carrying the marker 28 should be at the back of the book, and the first page of the record is placed in rear of the marker, and the back cover then locked upon the posts.

60 When subsequent pages of the book are to be written, the respective leaves are removed from the front of the book to receive the records and then placed successively on the back of the book. The written pages therefore 65 fore always appear in regular order back of

the marker 28, and those pages in front of the marker are blank. By operating the book in this manner no pages are removed at any time excepting those actually in use by the copyist, and the book can be kept 70 upon the shelf for reference purposes at all times excepting the brief periods required for removing or inserting the leaves. No occasion ordinarily arises for inserting or removing leaves from the middle of the book. 75 The clerk in charge of the book may keep possession of the key, so that no unauthorized person can either insert or remove a leaf. When the book is filled with records, the binding is made permanent and secure 80 by locking the slides 14 in some suitable manner, as heretofore described.

Having described my invention, what I claim, and desire to secure by Letters Patent, is—

1. A loose-leaf binder comprising a back, a pair of covers suitably hinged to the back, a pair of casings connected with the back and covers adjacent to the hinges thereof, a locking-slide in each casing, said casings and slide being provided with correspondingly-located openings, a series of posts, each end of each post being adapted to enter an opening in the adjacent casing and slide and to interlock with the slide, and means for permanently securing each slide in engagement with the adjacent ends of the posts, whereby a permanently-bound book is secured when desired the leaves of which cannot be removed.

2. In a loose-leaf binder, the combination with a plurality of independent posts, of a pair of casings arranged longitudinally of the binder and having openings to receive the ends of the posts, means within the casings 105 for locking the casings to the posts, and a common metal plate to which both casings are hinged.

3. In a loose-leaf binder, the combination with a plurality of independent posts, of a pair of casings arranged longitudinally of the binder and having openings to receive the ends of the posts, means within the casings for locking the casings to the posts, and a common curved plate to which the casings 115 are hinged, said plate serving to hold the casings in the proper relation to each other and to stiffen the back portion of the book.

4. In a loose-leaf binder, the combination with a pair of covers and a suitable back connecting the covers, of a pair of casings connected respectively to the covers and each having openings to receive the ends of a series of posts, means within the casings for locking the posts to the casings, a series of posts adapted to enter the openings in the casings and engage with said locking means, independent register-plates having openings adapted to register with the openings in the casings, and fly-leaves connected to said reg- 125 130

ister-plates, the said register-plates being adapted to receive the ends of the posts to cause them to register with the openings in the casings, substantially as set forth.

5. In a loose-leaf binder, the combination with a pair of covers and a suitable back connecting the covers, of a pair of casings connected respectively to the covers and each having openings to receive the ends of a series of posts, means within the casings for locking the posts to the casings, a series of posts adapted to enter the openings in the casings and engage with said locking means,

and independent register-plates having openings adapted to register with the openings in the casings, the said register-plates being adapted to receive the ends of the posts to cause them to register with the openings in the casings, substantially as set forth.

In testimony whereof I affix my signature in presence of two witnesses.

REES F. PARRY.
